UNITED STATES PATENT OFFICE.

ROBERT C. ALBURY AND LEFFY T. HAYMAN, OF TAMPA, FLORIDA.

AUTOMATIC STOP MECHANISM FOR RAILROADS.

1,380,174.

Specification of Letters Patent. Patented May 31, 1921.

Application filed December 28, 1920. Serial No. 433,726.

To all whom it may concern:

Be it known that we, ROBERT C. ALBURY and LEFFY T. HAYMAN, citizens of the United States, residing at Tampa, in the county 5 of Hillsborough and State of Florida, have invented certain new and useful Improvements in Automatic Stop Mechanism for Railroads, and do hereby declare the following to be a full, clear, and exact description of the invention, such as will enable others skilled in the art to which it 10 pertains to make and use the same.

The present invention relates to improvements in automatic stop mechanism for railroads, and has for an object to provide an improved device adapted to be mounted on the locomotive whereby the throttle will be automatically closed and the air brakes applied whenever the locomotive carrying the 15 apparatus shall approach within a predetermined distance of another locomotive so equipped, or shall approach an open switch, open draw bridges, and the like dangerous 20 conditions.

Another object of the invention is to provide a simple and inexpensive apparatus for carrying out the above described objects which may be mounted in conjunction with the usual parts of present type locomotives 25 30 without any alteration in the construction of the latter.

A further object of the invention is to provide an apparatus of this character which shall be under the direct and ready 35 control of the engineer, and which will give a signal in the cab in addition to applying the brakes and shutting off the steam.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a diagrammatic view showing the two locomotives equipped with mechanisms constructed according to the present invention;

Fig. 2 is a view in side elevation of the third rail contact wheel;

Fig. 3 is a front view of the same;

Fig. 4 is a fragmentary elevational view of the throttle lever and associated parts;

Fig. 5 is a fragmentary perspective view 55 of a construction of rails adjacent a draw bridge; and

Fig. 6 is a fragmentary plan view of a switch with a contact device applied thereto and constructed according to the invention. 60

Fig. 7 is a detail side elevation of one type of throttle lever and locking means therefor which may be used in carrying out the present invention.

Referring more particularly to the drawings, and at present to Fig. 1, A and B represent in diagram two locomotives running toward each other on the rails 1 and 2 of the single track shown.

The locomotive A is provided with an 70 insulated bracket 3 for carrying a contact wheel 4 running on a third rail 5.

The throttle lever for the locomotive A is represented at 6 and is pivoted at 7, it having the usual locking dog 8 coöperating 75 with the toothed segment 9. The engineer draws the lever 6 to the left in order to open the throttle, and in the drawing the throttle valve is in partially open position. According to the invention a coil spring 10 is 80 connected to the throttle lever 6 and to the boiler head or some other fixed part in the engine cab. The function of this spring is to tend to draw the lever 6 toward the right or to a closed position whenever the 85 latch dog 8 is disengaged from the segment 9. The spring 10 is put under tension as the lever 6 is moved toward the left to open the throttle wider.

According to the invention a perforated 90 lug 11 extends from the latch dog 8 and slides loosely over the upper end of a rod 12 which carries a collar 13 adapted to be brought up beneath the lug 11 in order to raise the dog 8. The rod 12 is provided 95 with a pivot joint 14 to enable it to swing about with the lever 6 and latch dog, and for this purpose the collar 13 is placed a distance beneath the lug 11.

The rod 12 extends slidably down into a cylinder 15 where it carries a piston head or plunger 16 normally urged to a lowermost position by means of a coil spring 17 within the cylinder. A vent tube 18 extends outwardly from the cylinder at a suitable point 100 so that it may be uncovered when the plunger 16 rises under the influence of compressed air received from the air line of the 105

train through a conduit 19. The conduit 19 includes a valve casing 20 in which is placed a valve 21 normally closed and preventing the ingress of air from the train line. The 5 valve stem 22 extends upwardly through the casing and is connected to a lever 23 pivoted as at 24. The free end of the valve lever 23 projects in the path of a cam 25 on the shaft 26 of an electric motor 27.

10 The motor 27 is adapted to be placed in circuit with a generator 28 driven constantly by the locomotive, the circuit wires being indicated by 29 and 30. The latter wire 30 includes a normally open switch 31 adapted 15 to be closed by a relay 32. The upper portion of the wire 30 is also included in the relay circuit. The relay 32 is placed in parallel with a lamp 33 included in a wire 34 by means of a conductor 35. A wire 36 joins both wire 20 34 and wire 35 with a contact plate 36' mounted fixedly on a base plate 37. This base plate 37 and its appurtenant parts are more clearly disclosed in Fig. 4.

A coil spring 38 tends to draw the lower 25 end of a lever 39, fulcrumed at 40 on the base plate, against the contact plate 36'. The lever 39 has on its upper end a hook 41 for engagement with a hook 42 on a pivoted latch 43 when the lever 39 is swung out of 30 engagement with the contact plate 36'. A coil spring 44 tends to draw the latch 43 upwardly when the hooks 41 and 42 are released. The latch 43, is grounded through wire 46, while a lead 47 connects the lever 35 39 with the contact 48 of a double throw switch 49 which is mounted in the locomotive cab convenient to the hand of the engineer.

The pole 50 of the switch is connected by 40 a lead 51 with one side of the generator 28, the same side of the generator being connected by a wire 52 with the uppermost right hand pole 53 of said switch. The pole 54 of the switch is connected by a wire 55 45 with the lead 47. One of the intermediate poles 56 of the switch is connected by a wire 57 to contact wheel #4, while the other intermediate pole 58 is grounded by a lead 59 on the locomotive framework.

50 The opposite locomotive is provided with an insulated bracket 60 carrying a contact wheel 61 also running upon the third rail 5.

A wire 62 grounds the pivoted latch 63 on the base board 64 which is mounted in 55 the cab of the locomotive B. The latch 63 engages the lever 65 in a similar manner to corresponding parts on the locomotive A and coöperates in a similar manner with the control plate 66 on the lower portion of the base board 64.

60 Similarly a projection 67 on the throttle valve lever 68 is adapted to strike the lever 65 when said lever 68 is swung toward the boiler head under the influence of the spring 65 69. The dog 70, carried by the throttle

lever, coöperates with the usual segment 70' and is provided with a perforated lug 71 loosely engaging over the upper end of a vertically reciprocating rod 72 which carries a collar 73 adapted to engage beneath the 70 lug to lift the latch from the segment.

The rod 72 is provided with a pivoted joint 74 and with a plunger 75 at its lower end reciprocating in a vertically disposed cylinder 76 in which is also placed a coil 75 spring 77 normally tending to drive the plunger 75 downwardly and to keep closed the vent 78. Air from the air line is adapted to enter the cylinder 76 through a conduit 79 which contains a valve casing 80 having 80 a valve 81 therein normally closed and provided with a stem 82 connected to one end of a lever 83 which is disposed in the path of a cam 84 on the shaft 85 of an electric motor 86.

85 The motor is driven by current received from a generator 87 which is continuously driven by the locomotive. The wire 88 connects the generator and motor at one side, while the wire 89 connects these parts at 90 the other side, an open switch 90 being interposed between the latter and adapted to be closed by a relay 91. This relay is included in circuit with the generator 87 by means of the upper portion of the wire 89 95 and by an additional wire 92 which is connected to the contact plate 66 on the base plate 64. A wire 93 is in multiple with the wires 89, 92 and contains a lamp 94 placed in the cab of the locomotive B.

100 The opposite side of the generator 87 is connected by wires 94 and 95 respectively with the poles 103 and 101 of a switch 98 also mounted in the cab of the locomotive B. A wire 99 connects the pole 100 of the switch 105 with the frame of the locomotive B. A switch pole 97 is connected by a wire 102 with the lever 65 on the base board 64. The switch pole 96 is connected by a wire 104 with the wire 102. The pole 105 of the 110 switch is connected by a lead 106 on part 61.

115 Referring more particularly to Figs. 2 and 3, one of the contact wheels on the third rail is shown. The construction of both the third rail contact wheels 4 and 61 is the same and the wheel is a flanged wheel somewhat similar to, although preferably smaller than, the usual locomotive wheels; and this contact wheel is mounted in forks 107 extending downwardly from a bed plate 108. 120

A second cap plate 109 is situated above the bed plate 108 and is spaced thereabove, coil springs 110 being interposed between the two plates through which bolts 111 are passed for securing the plates together and for placing the springs under the desired compression. The springs provide for the upward yielding of the wheel when passing over rail joints or when encountering obstacles. The cap plate 109 is preferably 130

formed in one piece and constitutes an angle iron construction together with a vertical plate 112 provided with openings 113 to receive fastenings by which the wheel unit 5 may be secured to an appropriate part of the locomotive framework.

In Fig. 4 is shown one of the base plates 64 carrying the pivoted catch, the circuit interrupting lever, and the contact plate. 10 These parts have been heretofore described and they are here shown in both positions.

Referring more particularly to Fig. 5, the rails 1 and 2 on which the locomotive moves are bonded together by a bar 114. The 15 third rail is as indicated at 5, and the construction is shown to be adjacent an open draw bridge which, when closed, causes the movable rails to seat upon the projecting base plates 115 and 116 extending outwardly 20 from the rail 1 and the third rail 5. A contact joint 117 is in connection with the rail 2, while a second contact plate 118 is carried by the free end of a lever 119 pivoted as at 120 to the tie 121 or other suitable 25 part. This lever 119 is also connected by a lead 122 with the third rail 5. The lever carries a platform 123 at its free end to be engaged by a part of the draw bridge whereby when the draw bridge is closed, it 30 will automatically depress the platform 123 and lever 119 opening the contacts 117 and 118 and placing the spring 124 under a condition of tension.

When the draw bridge is opened the 35 spring 124 will cause the closing of the contacts 117 and 118 and this will cause the automatic stopping of the locomotive as hereinafter described.

In Fig. 6 the main line rails are indicated 40 at 1 and 2, while the switch points are represented at 125 and 126. These switch points are connected to the usual switch operating mechanism 127 which is extended as indicated at 128 and carries a contact 129 adapted to be closed against a similar contact 130 carried by the third rail 5. When the siding is open the contacts 129 and 130 will be closed and they will therefore operate to arrest the movement of any locomotive 45 approaching the switch, as hereinafter described.

In operation, referring to Fig. 1, assuming, as regards locomotive B, that the throttle lever 68 is in the position shown, and 50 that the locomotive B is proceeding along the tracks 1 and 2 in the direction indicated by the arrow, and further assuming that the switch 98 is in the lower position, a circuit through the generator 87 will be closed as follows: From the generator 87 through wire 95 to switch pole 101, pole 100 and through wire 99 to the frame of the locomotive B and track 2 where the current is grounded. Assuming locomotive A to have 55 its throttle lever 6 also in the running posi-

tion shown; to be moving in the direction indicated by the arrow; its switch 49 in the upper position: the locomotive A transmits current from track 2 to wire 59, poles 58 and 54 of switch 49, wire 55, and 60 to wire 47; thence through lever 65, contact plate 36', wire 36, branch wires 34 and 35 and relay 32 to generator 28. From generator 28 through wire 52, contacts 53 and 56 of switch 49, wire 57, and contact wheel 4 to third rail 5. Back through third rail 5, contact wheel 61 of locomotive B, wire 106 to pole 105 of switch 98, contact 96 of the switch, wire 104, wire 102, lever 65, contact plate 66, wires 92 and 93 to wire 89 and relay 91. Distance between locomotives A and B consumes current to the extent that relay 91 is not sufficiently energized to close switch 90.

When locomotives approach each other, 85 the resistance of the rails and ground is reduced until finally current is sufficient to energize relay 91 for closing the switch 90 and directing current from the generator 87 to the motor 86. When the relay 91 is 90 energized, the current effecting such operation is divided sufficiently for lighting the lamp 94 to give visual signal to the effect that a train is approaching in an opposite direction. 95

The current will also traverse the windings of the relay 91 and cause the closing of the switch 90, thereby placing the motor 86 in closed circuit with the generator 87 through the branch wires 88 and 89. The 100 motor will revolve causing its cam 84 to project beneath the lever 83 to thereby lower the valve 81 from its seat, permitting air from the train line to enter the conduit 79 by which it is conveyed to the compressed air 105 cylinder 76.

Here it will have the effect to raise the plunger 75 and consequently the rod 72, carrying the collar 73 upwardly against the lug 71 thereby lifting the latch dog 70 from the segment 70' and leaving the throttle lever 68 free to be closed by the spring 69. The plunger 75 will be raised past the vent 78 which will bleed the train line and apply the air brakes in the usual manner. 110 115

When the throttle lever 68 is moved by the spring 69 toward the left, which is the closed position, the pin 67 thereon will strike the lever 65 above its pivot point and will consequently swing it in such direction as to engage the hooks 41 and 42 whereby to make the electrical contact between the catch 63 and the lever 65. 120

The pivoted catch 63 may be swung down against the tension of its spring 44 into interlocking engagement with the lever 65 so as to complete a circuit through such parts and wherein the latch 63 is grounded through wire 62 and the current passes through such wire and latch, through lever 125 130

65 and wire 102, wire 104, contact 96, pole piece 105, and out to the third rail 5 through wire 106 and contact wheel 61.

From contact wheel 61, rail 5, contact 5 wheel 4, wire 57, switch poles 56 and 53, wire 52, generator 28, branch wires 34 and 35 to wire 36, contact plate 36', lever 39 and, if throttle is closed, back to ground through wire 46. If throttle is open, through lever 10 39 to wire 55, switch poles 54 and 58 and wire 59 where the current is grounded in locomotive A.

The pivoted lever 65 is normally out of contact with the latch 63 and is only closed 15 in circuit therewith when the engineer is aware that there is trouble ahead and he may then connect the lever 65 with the latch 63 as above described to protect himself from another train by merely closing the 20 circuit of the other train through his apparatus for automatically releasing the throttle on the approaching train.

A like operation will take place in the locomotive A and it will be noted that the 25 switches 49 and 98 are swung into opposite positions, such as with the switch 49 of the locomotive A in raised position and the switch 98 of the locomotive B in lowered position. This adjustment of the switches 30 is necessary in order to have the current flow in the same direction through the apparatus in both of the locomotives.

A like operation will take place in the locomotive A. A circuit will be closed 35 through the generator 28 which will include the locomotive B, and its contact wheel 61 and the generator 28 will furnish current to the motor 27 when the switch 31 is closed. The motor will open the valve 21 allowing compressed air to enter the cylinder 15 and raise the piston 16 therein which will operate by previously described parts to release the throttle valve 6 and allow it to be drawn 40 by its spring 10 to a closed position. The 45 air will find escape to the vent 18 and the brakes will be applied.

The circuits from the generators to the motors will be kept closed until the engineers move their switches 49 and 98 from 50 the upper to the lower position, which will cause an interruption of the circuits.

In the case of the drawbridge shown in Fig. 5, as soon as the draw is open the rails 1 and 2 and the third rail 5 are placed in 55 contact through the lever 119 and the contact points 117 and 118. It is obvious, therefore, that the circuit from the generator of an engine approaching the draw bridge will pass from the third rail 5 and the rails 1 60 and 2 and will be closed through its generator so as to apply the brakes and shut off the steam in the manner heretofore described.

A similar result will be had when the 65 switch shown in Fig. 6 is open. The contacts

129 and 130 will be closed, thus placing the third rail 5 and the rails 1 and 2 which are bonded together in a closed circuit and when the locomotive approaches the open switch it will be stopped by a circuit through the 70 rails and through its generator in the manner previously described.

It is obvious that various changes and modifications may be made in the details of construction and design of the above specifically described embodiment of this invention without departing from the spirit thereof, such changes and modifications being restricted only by the scope of the following claims.

What is claimed is:

1. In combination, a railway, a locomotive thereon, a third rail, contact means carried by and insulated from the locomotive and engaging the third rail, means carried by the locomotive and connected between the locomotive frame and said contact means for automatically shutting off power from the locomotive and applying air brakes, and means for optionally closing a circuit 90 through said locomotive frame and contact means to the exclusion of said automatic means, substantially as described.

2. In combination, a railway, a locomotive thereon, a third rail, contact means carried by and insulated from the locomotive and engaging the third rail, means carried by the locomotive and connected between the locomotive frame and said contact means for automatically shutting off power from the locomotive and applying air brakes, and means for changing polarity of the current through the locomotive frame for directing the current flow in the same direction as that through a second locomotive approaching the first locomotive, and means for optionally closing a circuit through the locomotive frame and contact means to the exclusion of said automatic means, substantially as described.

3. In combination, a railway, a locomotive thereon, a third rail, contact means carried by and insulated from the locomotive and engaging the third rail, means carried by the locomotive and connected between the 115 locomotive frame and said contact means for automatically shutting off power from the locomotive and applying air brakes, means for optionally closing a circuit 120 through said locomotive frame and contact means to the exclusion of said automatic means, and means for changing the polarity of the current through the locomotive frame for directing the current flow in the same direction as that through a second locomotive 125 approaching the first locomotive, substantially as described.

4. In combination, a railway, a third rail insulated therefrom, a locomotive on the railway, contact means carried by and insu-
